CLAIM

The ornamental design for a seatbelt accessory attachable to existing vehicle seatbelt for lengthening purposes, as shown and described.

DESCRIPTION

FIG. 1 is a front elevational view of the seatbelt accessory attachable to existing vehicle seatbelt for lengthening purposes showing my new design;

FIG. 2 is a rear elevational view thereof;

FIG. 3 is a right view thereof;

FIG. 4 is a left side thereof;

FIG. 5 is a top plan view thereof;

FIG. 6 is a bottom plan view thereof; and,

FIG. 7 is an isometric view thereof.
